UNITED STATES PATENT OFFICE.

INGEBRET BÖHN, OF SÖRUMSANDEN, NORWAY.

TUNNELING-MACHINE.

1,328,118.

Specification of Letters Patent. Patented Jan. 13, 1920.

Application filed December 4, 1917. Serial No. 205,369.

To all whom it may concern:

Be it known that I, INGEBRET BÖHN, a subject of the King of Norway, residing at Sörumsanden, in the Kingdom of Norway, have invented certain new and useful Improvements in Tunneling-Machines; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 This invention relates to tunneling machines of the kind which cuts away the rock without the aid of explosives and has for its object a driving mechanism for the cutters in machines of this kind.

20 In accordance with the invention the reciprocating cutters are moved by means of a disk performing an oscillating movement about its center, and the edge of which is connected directly or indirectly with the 25 reciprocating cutters. The said disk may receive its movement from a crank or the like at one end of a rotating shaft, said crank being connected with the oscillating disk by means of a rod, which is moved by 30 means of the crank in such a manner that it describes a conical surface, the apex of which is the center of the disk. The disk connected to the rod will then perform the necessary oscillating movement.

35 In the accompanying drawing the figure is a longitudinal vertical section diagrammatically illustrating a machine embodying the invention.

The rock cutters 1 are mounted in an 40 annular row and are guided through holes in a support 2 in front of the machine.

The back ends of said rock cutters 1 are connected by means of balls and sockets 3 to a disk 4 which in turn is supported at its 45 center on a part 6 of the machine by means of ball and socket 5.

The said disk 4 is fastened to the forked end of a rod 7, the other end of which projects loosely through an eccentric boring 8 50 in a rotating disk 9. The disk 9 is mounted on the shaft 10 of a motor 11 or the like.

The rock cutters as well as disk 4 and motor 11 are mounted in a drum 12 which is supported on rollers 13 on a car- or truck 55 frame 14. Drum 12 at its rear end is pro-

vided with an internal gear 15, engaged by pinion 16, which is driven from motor 11 by means of shaft 17, gears 18 and shaft 19. Motor 11 also acts to perform the feeding movement of the drilling machine by means 60 of the shaft 17, gears 20, 21, worm gear 22 and pinion 23, engaging teeth on the carrying wheel 24.

As the rod 7 is loosely connected to the crank disk 9, the disk 4 will not be rotated 65 by the action of the crank disk relatively to the drum 12 and the support 2. The support 6 is fixed in the drum and extends through the forked end of the rod 7 so that any great amount of rotation of the disk 4 70 on the ball 5, caused by a back pressure exerted by the drills in operation, is prevented by the forked end of rod 7 engaging the support 6.

When the machine is working, the cutters 75 1 are reciprocated by means of disk 4 thus hammering on the tunnel wall. At the same time the drum 12 is slowly rotated so that the rods 1 are working along a circular path 80 of the tunnel wall during the forward movement of the whole machine.

I claim:

1. In a tunneling machine, a plurality of reciprocating cutter bars, a guide for the latter, a centrally pivoted oscillatory disk, 85 universal connections between the cutters and disk, and means to impart an oscillatory movement to the latter, whereby the cutter bars are reciprocated.

2. In a tunneling machine, a plurality of reciprocating cutter bars, a guide for the latter, a centrally pivoted oscillatory disk, ball and socket joints connecting the cutters and disk, and means to impart an oscillatory movement to the latter, whereby the cutter 95 bars are reciprocated.

3. In a tunneling machine, a plurality of reciprocating cutter bars, a guide for the latter, a centrally pivoted oscillatory disk, ball and socket joints connecting the cutters 100 and disk, means to impart an oscillatory movement to the latter, whereby the cutter bars are reciprocated, and means to simultaneously rotate the disk and guide.

4. In a tunneling machine, a plurality of 105 reciprocating cutter bars, a guide for the latter, a centrally pivoted oscillatory disk, ball and socket joints connecting the cutters and disk, a rod connected to the rear side of the disk coaxially with the same, and 110

means for revolving the rear end of the rod to move the axis thereof in a conical path and thereby oscillate the disk, whereby the cutter bars are reciprocated.

5. In a tunneling machine, a plurality of reciprocating cutter bars, a guide for the latter, a centrally pivoted oscillatory disk, ball and socket joints connecting the cutters and disk, a rod connected to the rear side of the disk coaxially with the same, means for revolving the rear end of the rod to move the axis thereof in a conical path and thereby oscillate the disk, whereby the cutter bars are reciprocated, and means to simultaneously rotate the disk and guide.
- 10
- 15

6. In a tunneling machine, a rotatable drum, a guide member carried thereby, cut-

ter bars reciprocably mounted in the latter, a ball bearing fixed in the machine frame, an actuating disk axially mounted on said bearing, ball and socket joints connecting the disk and cutter bars, an actuating rod fixed to the rear side of the disk co-axially therewith, a crank member loosely connected to the free end of the actuating rod, and means whereby the drum and crank member are rotated simultaneously.

In testimony that I claim the foregoing as my invention, I have signed my name in presence of two subscribing witnesses.

INGEBRET BÖHN.
